(57) **CLAIM**

I claim the ornamental design for an LED fog lamp, as shown and described.

DESCRIPTION

FIG. 1 is a front perspective view of a design of the LED fog lamp;

FIG. 2 is a front elevation view of the LED fog lamp of FIG. 1;

FIG. 3 is a rear elevation view of the LED fog lamp of FIG. 1;

FIG. 4 is a first side elevation view of the LED fog lamp of FIG. 1;

FIG. 5 is a second side elevation view of the LED fog lamp of FIG. 1;

FIG. 6 is a bottom plan view of the LED fog lamp of FIG. 1; and,

FIG. 7 is a top plan view of the LED fog lamp of FIG. 1. The features shown in broken lines depict environmental subject matter only and form no part of the claimed design.

1 Claim, 7 Drawing Sheets
